UNITED STATES PATENT OFFICE.

WILLIAM A. KRAEMER, OF CHICAGO, ILLINOIS.

CRUSHER.

1,282,870.

Specification of Letters Patent.

Patented Oct. 29, 1918.

Application filed January 28, 1918. Serial No. 214,039.

To all whom it may concern:

Be it known that I, WILLIAM A. KRAEMER, a citizen of the United States, residing at Chicago, in the county of Cook and State of Illinois, have invented certain new and useful Improvements in Crushers, of which the following is a specification.

My invention relates to crushers and has for its primary object the provision of an improved device of this character adapted for crushing sugar, salt and similar substances of a hygroscopic character whereby an improved crushing element traveling along a pressure resisting wall resiliently presses upon lumps of material to reduce them to a finely divided state and is angularly adjustable with respect to the wall. A further object is the provision of a crushing plate mounted for limited oscillation with respect to a bar upon which it is carried as well as for bodily adjustment with said bar as respects the surface of the pressure resisting wall.

A further object is the provision in a crusher of an open bottom hopper together with a pressure resisting wall engaging the lower edge of the hopper and apertured for communication therewith and a crushing element below said wall resiliently pressed against the wall on the side opposite to the hopper, said element being longer than the aperture in the wall so that as the element passes the aperture, it is retained from entering the hopper by having its ends constantly guided against the wall at the ends of the aperture.

Other objects and advantages of my invention will appear from the following description taken in conjunction with the accompanying drawings which form a part of this specification and illustrate the preferred embodiment of my invention.

In the drawings:

Figure 1 is a side elevation of my invention showing the lower portion of the hopper together with the crushing chamber and parts associated therewith in section substantially on a centrally vertical transverse plane; Fig. 2, is an end elevation thereof; Fig. 3, is a section taken on line 3—3 of Fig. 1; Fig. 4, is an enlarged side elevation broken away and of one of the crushing plates together with the bar upon which the same is carried.

Reference numeral 10 indicates generally the frame of the crusher which supports at its upper end a hopper 11 having an open bottom. End plates 12 are supported in any suitable manner in the frame, carrying the cylindrical, foraminated, pressure resisting wall 13, preferably in the form of a heavy screen. This wall engages the lower edge of the hopper 11 and is apertured for passage of material from the hopper into the chamber formed by the wall. Reference numerals 14 and 15 indicate those portions of the screen which define the ends of the communicating aperture between the hopper and the crushing chamber. A lined axle bearings 16 are provided preferably in the plates 12, and carry a rotatable axle 17 which, at one end, supports the idling pulley 18 and driving pulley 19. Within the pressure chamber and preferably at the extreme ends thereof the axle 17 carries a pair of spiders 21 each of which carries radially extending arms 22 projecting oppositely in pairs from the respective spiders. The spiders themselves are keyed as at 23 to the axle. The arms 22 are all of equal length and terminate short of the wall 13, the axle 17 being concentric with the wall. At their tips the arms 22 are formed with hollow bearings 24 into which fit the rounded ends 25 of bars 26. These bars, as best seen in Fig. 3, are preferably rectangular and have their adjoining surfaces 27 and 28 meeting on an edge 29 which is projected toward, but spaced somewhat from the pressure resisting wall 13. Preferably the faces 27 and 28 of each bar 26 form angles of 45° with the plane defined by the axis of the upper bar and the axis of the axle 17 so that a considerable angle is formed between the arcuate wall 13 and the surfaces 27 and 28. At intervals each bar is radially transfixed by a threaded dowel pin 31 which engages threaded apertures provided at intervals in each bar. The tips 32 of these pins project through the edge 29 and toward the wall 13 in each instance, though preferably terminating short of the wall.

At 33 is shown the crushing plate of my invention preferably formed of a piece of thin webbed angle bar, the back web 34 of which overlies surface 28 of the bar 26 and the forward crushing web 33 of which overlaps surface 27. The webs 33 and 34 are

right-angled as are the surfaces 27 and 28 of the bar. The angle of the plate formed by webs 33 and 34 is pierced for engagement by the tips of the dowel pins 31, these pins fitting loosely within the apertures of the plate in order that the plate may, in operation, oscillate through a limited path on an axis parallel to edge 29. Each bar 26 is formed with spring recesses opening from the faces 10 27 and 28 and springs 36 are bottomed in these recesses and press outwardly against the inner surfaces of webs 33 and 34, thereby holding the crushing plate spaced from the bar and with its angle in contact with 15 the wall 13 as seen in Fig. 3. Because of the space left between the crushing plate and the bar, the bar is permitted the slight oscillation above described. In Fig. 1 will be seen set screws 37 by means of which the 20 bars 26 are held fixed in their bearings 24. If the character of material being crushed requires it, these set screws 37 may be loosened and each bar 26 adjusted about its own axis in order to lessen or increase the 25 angle formed between the wall 13 and the web 33 of the crushing plate. Such adjustment is indicated at 35 by dotted lines in Fig. 3.

In the operation of my invention, and 30 considering the crusher chamber as charged with material fed from the hopper, power is applied to pulley 19 to rotate the axle 17, bars 26 and crushing plate 33. This results in moving the crushing plates in the direction of the arrow shown in Fig. 3. Material caught between the wall 13 and the web 33 will be crushed to a finely divided state and forced through the wall. Should the material being crushed contain extremely hard 40 lumps of foreign matter these lumps will pass between the wall and the angle of the crushing plate depressing springs 36 and preventing distortion of the wall. Should a large lump of material fill the angle 45 formed by the wall and the crusher plate, the plate will yield until it strikes the surface 27 of the bar whereupon the lump will be crushed and the rebound of springs 36 will start the crushed material out through 50 the wall 13 before the material packs within the angle.

From Fig. 1 it will be seen that the extremities of each crushing plate 33 will bear against the portions 14 and 15 of the wall 55 13 of the crushing chamber so that the springs 36 can never force the crushing plates upwardly into the hopper. Preferably the crushing surface of the plate 33 is knurled as shown in Fig. 4 in order that 60 it may readily hold lumps to be crushed.

While I have illustrated and described the preferred embodiment of my invention, it is obvious that one skilled in the art may make modifications thereof without departing 65 from the spirit of the invention. I

wish, therefore, not to be restricted to the precise embodiment shown except in so far as the same is limited in the appended claims.

I claim:

1. In a crusher, the combination with a pressure resisting wall, of a bar movable along the wall, and a crushing plate swingingly supported on the bar and yieldingly held spaced therefrom and in contact with 75 said wall.

2. In a crusher, the combination with a pressure resisting wall, of a bar movable along the wall and in spaced relation thereto, said bar having two angularly related 80 faces the meeting edge of which parallels the wall and is projected toward the same, a crushing plate comprising an angle bar of less thickness than the distance from said meeting edge to the wall, the webs of which plate meet at an angle substantially that of said angularly related faces, said webs respectively overlying said faces, dowel pins carried in the bar and projecting loosely through apertures provided in the angle of 85 said plate, and springs interposed between the bar and each web of the plate. 90

3. In a crusher, the combination with a pressure resisting wall apertured for communication with a hopper, of a bar spaced 95 from the wall and movable in parallelism therewith, and a crushing plate carried by the bar and resiliently pressed against the wall; said plate being longer than the aperture in the wall. 100

4. In a crusher, the combination with a pressure resisting wall apertured for communication with a hopper, of a bar spaced from the wall and movable in parallelism therewith, and a crushing plate longer than 105 said aperture, carried by the bar, resiliently pressed against the wall, and mounted for oscillation about an axis positioned between the bar and wall.

5. In a crusher the combination with a pressure resisting wall, and supporting arms movable in parallelism therewith, of a bar fixed in said arms, adjustable therein about an axis parallel to the wall, said bar being spaced from the wall, and a crushing plate mounted on the bar and yieldingly pressed 110 against the wall. 115

6. In a crusher, the combination with a pressure resisting wall, and supporting arms movable in parallelism therewith, of a bar fixed in said arms, adjustable therein about an axis parallel to the wall, said bar being spaced from the wall, a crushing plate mounted on the bar for limited oscillation about an axis positioned between the bar and wall, and springs normally holding said plate against the wall and spaced from the body of the bar. 120 125

7. In a crusher, the combination with a cylindrical, foraminated, pressure resisting 130

wall, of an axle concentrically rotatable therein, supporting arms radiating from the axle, a bar fixed in said arms, adjustable therein about an axis parallel to the wall, 5 said bar being spaced from the wall, longitudinally adjustable dowel pins transfixed in the bar and projecting therefrom toward said wall, a crushing plate overlapping two sides of the bar and loosely doweled on said pins, and springs normally holding said 10 plate against the wall and spaced from the bar.

In testimony whereof I affix my signature.

WILLIAM A. KRAEMER.
